GAS SAVING DEVICE

Plais R. Rowland, Manson, Wash.

Application March 10, 1950, Serial No. 148,788

8 Claims. (Cl. 123—119)

1

This invention relates generally to devices for improving the fuel economy of internal combustion engines, and pertains more particularly to a device of this character which has new and improved means for returning unburned fuel that has blown past the pistons into the crankcase or has been exhausted from the engine to the combustion chamber.

The primary object of this invention is to effect an economy in the fuel consumed by internal combustion engines by recovery of and the effective burning of unburned fuel that blows past the pistons and also that which is simply exhausted from the engine.

Another important object of the present invention is to protect the engine oil and also the engine from the deleterious effects to both, upon unburned fuel diluting the oil, and products of combustion such as water and sulphur dioxide mixing with the engine oil to give the same corrosive properties.

Another important object of this invention is to attain both lubrication of moving parts as well as the fuel value from oil vapors that customarily wastefully escape from the crankcase of an internal combustion engine.

Another important object of this invention is to provide a device capable of realizing the foregoing objects, without impairing the performance characteristics of the engine in the slightest degree regardless of load or speed conditions at which the engine is being operated.

A further important object of the present invention is to provide an apparatus of this character in accordance with the foregoing objects, which will be entirely automatic in operation, but which may be manually controlled as desired.

A still further object of this invention is to provide a device of this character which may be readily attached to conventional internal combustion engines, particularly those used in automobiles.

A meritorious feature of the present invention resides in the valves and the means for actuating the same whereby the introduction of fumes into the carburetor is controlled.

Another feature of the present invention resides in the provision of a mixing chamber, wherein vapors from the crankcase and the exhaust are mixed preparatory to the introduction of the same into the carburetor.

A final important feature to be specifically enumerated herein resides in the details of construction of the device, whereby the same may be readily and inexpensively manufactured, and yet

2

be durable and efficient for the purposes intended.

These, together with various ancillary features and objects of the invention which will later become apparent as the following description proceeds, are attained by the present invention, a preferred embodiment of which has been illustrated by way of example only in the accompanying drawings, wherein:

Figure 1 is a side elevational view of the present invention, showing the same used with an automotive internal combustion engine, the portion only of the automobile being shown in section;

Figure 2 is a top plan view of the invention as shown in Figure 1, with portions being broken away;

Figure 3 is a side elevational view of the mixing chamber, the same being shown partially in vertical section;

Figure 4 is a vertical sectional view of the push rod, the portion of the means for actuating the same being shown in dotted outline; and

Figure 5 is a vertical sectional view of the thermal actuated valve.

Reference is now made more specifically to the accompanying drawings, wherein like numerals designate similar parts throughout the various views, and in which a conventional automotive internal combustion engine is designated generally at 10.

The engine 10 includes a carburetor 12 which feeds combustible mixtures into an intake manifold 14 for the introduction of fuel into the combustion chambers, not shown, within the engine 10. The engine 10 further conventionally includes an exhaust manifold 16 which receives combustion products from the engine 10 and delivers the same through an exhaust pipe 18 to an exhaust muffler 20. The engine 10 further includes a crankcase 22, the interior of which is in communication with a breathing or filling pipe 24 having a cap 26.

As in conventional automobiles a fire wall 28 is disposed rearwardly of the engine 10, the lower edge of which fire wall 28 terminates at the forward edge of the floor board 30 in the vehicle driver's compartment. Carried by the fire wall 28 is a dash or instrument panel 32 which serves a purpose to be presently set forth.

The gas saving device which constitutes the subject matter of this invention comprises a combined vapor mixer and filter indicated generally at 34 and which is formed, as best shown in Figure 3, of a housing 36 that is open at its upper end and provided with a removable cap

38. The upper end of the casing 36 is internally threaded as 40 to threadingly receive a perforated bracket 42, which bracket 42 is provided with an internally threaded opening for threadingly receiving the lower end of the securing bolt 44. The bolt 44 slidably extends through an opening in the cover 38 and is provided at its upper end with a handle 46 for turning the bolt 44, the bolt 44 being provided with a retaining ring 48 secured thereon for urging the cap 38 toward the casing 36. In order to prevent leakage between the cap 38 and the casing 36, the periphery of the cap 38 is provided with a flange 50 embracing the upper end of the casing 36 and a sealing gasket 52 is disposed between the cap 38 and the casing 36. Filtering material such as steel wool 54 is disposed within the casing 36 below the bracket 42, and the casing 36 is provided with oppositely extending inlet nipples 56 and 58 adjacent the lower end of the casing 36, which nipples are in communication with an outlet nipple 60 adjacent the upper end of the casing 36.

Communication is provided between the breather pipe 24 and the crankcase and the interior of the casing 36 by means of a conduit 62 connected between the breather pipe 24 and the nipples 56, and a control valve 64 is provided in the conduit 62. In an analogous manner communication is provided between the interior of the muffler 20 and the casing 36 by means of a conduit 66 communicating therebetween and connected to the nipple 58, and which conduit 66 is provided with a control valve 68.

Indicated at 70 is a vacuum conduit that is in communication with the interior of the carburetor 12, and which conduit 70 is operatively connected to a vacuum actuated device such as windshield wipers, not shown. Communication is provided between the interiors of the casing 36 and the conduit 70 by means of a conduit 72 that has disposed therein a thermally actuated control valve 74 and a push valve 76.

The thermally actuated valve 74 is shown in detail in Figure 5 and comprises a housing 78 that is closed at opposite ends by couplings 80 that are connected into the conduit 72. A valve stem 82 attached to a valve 84 is disposed within the housing 78, the valve 84 being disposed to seat in a valve seat opening 86 provided in a transverse partition 88 so as to close communication between the opposite ends of the housing 78. A thermally responsive element such as a copper coil 90 is disposed within the housing 78 and has one end secured to the valve stem 82 and the other end secured to one of the couplings 80, the arrangement being such that a rise in temperature above a predetermined amount will cause the coil 90 to expand and through the valve stem 82 to unseat and open the valve 84. The valve stem 82 is guided in its longitudinal movement by being slidably received through an opening provided in a transverse guide bracket 92 disposed between the valve 84 and the coil 90. The valve 74 is held in heat exchange relationship with the exhaust manifold 16 by means of a supporting bracket 94 so that the valve 74 will open upon the exhaust manifold 16 rising above a predetermined temperature.

The push valve 76 is shown in detail in Figure 4 and comprises a body section 96 having a passage 98 therethrough, which passage 98 extends through oppositely extending nipples 100 for coupling the valve 76 in the conduit 72. The 75 from the conduits 62 and 66 are intimately

transverse recess 102 in the body 96 intersects the passage 98 and has slidable therein a valve 104 to which is connected a valve stem 106. Sealing means 108 including a bushing 110 are provided about the valve stem 106 and the upper end of the valve stem 106 is provided with a stop collar 112, and the valve 104 is normally urged into the position opening the passage 98 by means of a coiled compression spring 114 embracing the valve stem 106 and seated between the collar 112 in the bushing 110, the arrangement being such that the valve 104 is normally urged into the open position but is closed upon downward pressure on the collar 112.

Means is provided to progressively close the valve 104 upon the throttle setting of the carburetor 12 being reduced to idling position. Indicated at 116 is a throttle rod for actuating the throttle, not shown, of the carburetor 12, which it will be understood is moved vertically through the action of a bell crank 118 and a rod 120 that is controlled through the gas feed pedal, not shown, in the driver's compartment of the vehicle. A laterally projecting finger 122 is adjustably positioned on the throttle rod 116 by a split clamp 124, which finger 122 is disposed above the collar 112 of the valve 76 so that upon downward movement of the throttle rod 116 the finger 122 will depress the collar 112 to close the valve 76, it being readily apparent from Figure 1 that the throttle rod 116 moves downwardly upon the throttle of carburetor 12 being moved to idling position.

In addition, manual means are provided for closing the valve 76 which includes a control rod 126 slidably extending through the fire wall 28 and the instrument panel 32, the end of the rod 126 adjacent the instrument panel 32 being provided with a knob 128 whereby the same may be shifted longitudinally by the operator of the vehicle. An actuating lever 130 is pivoted intermediate its ends as at 132 and has one end pivotally secured to the end of the rod 126 remote from the knob 128, whereby pivotal movement of the lever 130 may be caused by manipulation of the knob 128. The end of the lever 130 remote from the end pivoted to the rod 126 is bent as at 134 for engagement with the stop collar 112, the arrangement being such that when the operator of the vehicle pulls inwardly on the knob 128 the lever 130 acts to close the valve 76, but when the knob 128 is moved forwardly from the vehicle operator's position the valve 130 pivots to a position permitting the valve 76 to open under the action of the spring 114.

The operation of the present invention will be readily understood. When the engine 10 is being operated the pressure prevailing within the intake manifold 16, the carburetor 12 and the vacuum conduit 70 will be below atmospheric pressure, while on the other hand the pressure prevailing in the muffler 20 and the breather pipe 24 will be above atmospheric, so that there will be a tendency at all times during engine operation for vapors to pass through both the conduits 62 and 66 to the mixing chamber 34 and thence through the conduit 72 to the vacuum conduit 70 and on in through the carburetor 12 to the intake manifold 16. Since the composition of the vapors in the muffler 20 and in the crankcase will be materially different, the valves 64 and 68 have been provided so that the proportion of flow in the conduits 62 and 66 may be controlled. The proportioned flows of vapor

mixed in the mixing chamber 34 and filter therein, whereupon the mixed vapors flow therefrom subject to the control of the valves 14 and 76 to the carburetor 12. The valve 74 functions to prevent the passage of vapors in the conduit 72 when the engine 10 is cold as upon starting, since one of the effects of the admission of vapors to the engine through the conduit 72 is to lean the mixture within the carburetor 12 and the intake manifold 14, and in view of the further fact that the vapors within the crankcase would be very lean due to the cold oil temperature and that therefore the performance of the engine 10 is not impaired in the slightest degree by the attachment forming the subject matter of this invention during starting, whereas as soon as the engine 10 has warmed up sufficiently to actuate the valve 74 into the open position, all the beneficial effects of the present invention may be realized to their fullest extent.

The function of the finger 122 carried by the throttle rod 116 in conjunction with the valve 76 is to prevent the flow of vapor through the conduit 72 during periods in which the engine 10 is being idled. It will be understood that the manual means provided for control of the valve 76 is not only a value to the operator of the engine in the sense that he may stop the operation of the present invention, but since the flow of vapor in the conduit 72 tends to increase the pressure within the vacuum conduit 70, such manual control is important in that the operator may adjustably reduce the flow of vapor through the conduit 72 so that vacuum actuated devices dependent upon the pressure differential existing between the vacuum conduit 70 and the atmosphere may be effectively actuated.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. In an internal combustion engine having an intake manifold and a carburetor for controlling the admission of combustible mixtures thereto and also including a crankcase and an exhaust, the combination with means for introducing vapors from the crankcase and also the exhaust into the intake manifold, means for proportioning the flow of vapors introduced into the intake manifold from the crankcase and the exhaust, means for mixing and also filtering the vapors introduced by said first means preparatory to introducing the same into the intake manifold, means responsive to the temperature of the engine for controlling the total flow of vapors introduced into the intake manifold by said first means, further means responsive to actuation of the carburetor for controlling the total flow of vapors introduced into the intake manifold by said first means.

2. In an internal combustion engine having an intake manifold and a carburetor for controlling the admission of combustible mixtures thereto and also including a crankcase and an exhaust manifold, the combination with means for in-

roducing vapors from the crankcase and also the exhaust manifold into the intake manifold, means responsive to the temperature of the engine for controlling the flow of vapors introduced by said last means into the intake manifold, and means responsive to the actuation of the carburetor for controlling the flow of vapors introduced by the first mentioned means into the intake manifold.

3. In an internal combustion engine having an intake manifold and an exhaust manifold, a carburetor for controlling the admission of combustible mixtures into the intake manifold, the combination with means for introducing vapor from the exhaust manifold into the intake manifold, means responsive to the temperature of the exhaust manifold for controlling the flow of vapor from the exhaust manifold to the intake manifold by the first mentioned means, and means responsive to actuation of the carburetor for controlling the flow of vapor from the exhaust manifold to the intake manifold by the first mentioned means.

4. In combination with an internal combustion engine having a carburetor, a crankcase and an exhaust; an improvement comprising a mixing chamber, a first conduit communicating between the crankcase and the chamber and a control valve therefor, a second conduit communicating between the exhaust and the chamber and a control valve therefor, a third conduit communicating between the chamber and the carburetor, a valve in the third conduit, said last mentioned valve being responsive to a predetermined engine exhaust temperature to open said third conduit.

5. In combination with an internal combustion engine having a carburetor, a crankcase and an exhaust; an improvement comprising a mixing chamber, a first conduit communicating between the crankcase and the chamber and a control valve therefor, a second conduit communicating between the exhaust and the chamber and a control valve therefor, a third conduit communicating between the chamber and the carburetor, a second valve in said third conduit, said second valve being responsive to actuation of the carburetor to open the third conduit.

6. In combination with an internal combustion engine having a carburetor, a crankcase and an exhaust; an improvement comprising a mixing chamber, a first conduit communicating between the crankcase and the chamber and a control valve therefor, a second conduit communicating between the exhaust and the chamber and a control valve therefor, a third conduit communicating between the chamber and the carburetor, a valve in the third conduit, said last mentioned valve being responsive to a predetermined engine exhaust temperature to open said third conduit, a second valve in said third conduit, said second valve being responsive to actuation of the carburetor to open the third conduit.

7. The combination of claim 6 including means for manually actuating said second valve.

8. A fuel saving attachment for use with internal combustion engines of the type that include a carburetor, a crankcase and exhaust comprising; a mixing chamber and porous medium therein, a first conduit communicating with the chamber having a control valve therefor and with which communication may be had with the interior of the crankcase, a second conduit communicating with the chamber having a control valve therefor and with which communication

may be had with the exhaust, a third conduit communicating with the chamber and with which communication may be had with the carburetor, a first valve in said third conduit and thermally responsive means for actuating the same, a second valve in said third conduit, means for manually actuating said second valve, and further means for actuating the second valve in response to actuation of the carburetor.

PLAIS R. ROWLAND.
